P. McLaughlin.
Cord Covering Mach.

N° 20,287

Patented May 18, 1858.

UNITED STATES PATENT OFFICE.

P. McLAUGHLIN, OF CAMDEN, MAINE.

MACHINE FOR WORMING, PARCELLING, AND SERVING THE RIGGING OF VESSELS.

Specification of Letters Patent No. 20,287, dated May 18, 1858.

To all whom it may concern:

Be it known that I, PATRICK McLAUGHLIN, of Camden, in the county of Waldo and State of Maine, have invented certain new 5 and useful Machinery for Worming, Parcelling, and Serving Rigging, of which the following is a full, clear, and exact description, reference being had to the accompanying drawing, making part of this specification, in which—

Figure 1 is a perspective view of the machine; Figs. 2, 3, 4, 5, 6, details to be referred to hereafter.

The rope used for the standing rigging of 15 vessels and other purposes where it is much exposed to the weather and to wear is generally covered. This is done by first laying spun yarn spirally around the rope in the interstices between the strands, and called 20 "worming." A covering of canvas put on by winding narrow strips around the rope is next applied. This is called "parcelling," and over this a continuous length of yarn is wound closely, the turns being in contact 25 with each other. This is called "serving."

To construct a machine to perform these operations with neatness and despatch is the object of my present invention.

That others skilled in the art may understand 30 and use my invention I will proceed to describe the manner in which I have carried out the same.

In the drawings A is the bed of the machine, to which are secured two ways B, having 35 on their upper edges the racks C, by which the carriage D is fed along. Studs *a* (two at each end) projecting from the lower side of this carriage slide in grooves *b* in the inner side of the ways B and steady 40 the carriage in its movements. From the carriage D, rise the posts E, F, G, H, I, and K which are braced together and steadied by the top brace L. Through suitable bearings in these posts passes the shaft M, to 45 which the power for operating the machine is applied. To a crank on the end of this shaft is attached a pitman *c*, which is connected by a rod *d*, to a short shaft *e*, supported in two blocks *f*, rising from the carriage D. Another rod *g* rises from the shaft *e*, and has pivoted to its outer end a pawl *h* that passes through a slot in the end of the carriage and engages with a ratchet 50 wheel N. The shaft which carries this wheel

has its bearing in the two studs *a* beneath 55 the carriage, and carries at each end a pinion O, which engages with the stationary rack C. Thus as the shaft M, is revolved the shaft *e*, is vibrated and the pawl *h*, feeds one notch of the wheel N, for each 60 revolution of the shaft M (the length of the rods *d*, and *g*, may however be varied so as to feed two notches if required). The revolution of the wheel N, moves the carriage along in the direction of its arrow. 65 Two pinions similar to O, support the rear end of the carriage.

To one end of the bed A, is secured a windlass P and from the other end rises a gallows Q, to which the rope to be operated 70 upon is attached after being passed through the machine. The windlass serves to draw the rope up taut, and keep it straight and stiff while being operated upon.

The mechanism by which the rope is laid 75 will now be described.

The mallet R has a hollow shaft through which the rope S, to be laid passes. This shaft is carried in suitable boxes *k*, in the posts E, and F. It has secured to it a 80 cogged wheel T, which engages with a wheel V, on the shaft M, and is thus revolved. From one side of the mallet R project two stanchions *i* which support the spools *l*. These spools carry the spun yarn *m*, to be 85 laid in the strands of the rope S, and the number of spools in use at any time will correspond to the number of strands in the rope (in the drawings to prevent confusion but one is shown occupied). Holes 1, 2, 3, 90 4, are made in the mallet one opposite to each spool. Through each one of these (as at 3,) is led a yarn *m*, from the spool *l*. These yarns are passed through into the hollow shaft of the mallet and the ends are 95 brought out of the shaft between the posts F and G, where they are attached to the rope S, one being laid in each strand of the rope. A guide block *n* (detached in Fig. 6) is inserted in a slot in one side of the mallet 100 R and passes through to the inside of the hollow shaft. Its inner edge is grooved to partially embrace the rope and is furnished with diagonal grooves 1, 2, 3, 4, whose inclination and distance apart correspond in a 105 measure to the lay of the strands of the rope. The yarns *m*, are received in these grooves and are pressed by the block *n*, against the

rope and are guided by it each into its proper space between the strands and are prevented from riding one over the other. This block is adjustable in its slot to suit 5 ropes of a different lay and is secured in place by a screw 7 passing through a small slot in the mallet. Thus as the carriage progresses the wheel T is revolved in the direction of its arrow, the mallet R is carried 10 around the rope and the yarns m, are laid in between the strands of the rope, one yarn for each strand, in a regular and uniform manner, and the rope is wormed. As the spools l are emptied they may be removed 15 to be filled or replaced by full ones, the ends of the fresh yarns being connected to the others. The rope after being wormed is parcelled in the following manner: Between the posts G, and H, is placed a mallet V, 20 the hollow shaft of which has its bearings in these posts and carries a cogged wheel W, which is driven in the direction of its arrow, an intermediate gear o engaging with it and with a gear p on the shaft M. This 25 mallet, shown detached in Fig. 2, carries a spool q, on which the strip of canvas or parcelling r is wound. It has cut in one side two diagonal slots 8 and 9 and in the side next the spool a larger slot in which is inserted 30 a guide block s, detached in Fig. 5, which is adjustable and is held in place by a screw 10 passing through a small slot in the mallet. One edge of this block is cut away in an inclined notch 11 (see Fig. 5,) which 35 gives the proper cant or inclination to the parcelling to make it lie around the rope with its edges just overlapping. The parcelling r is led from the spool q, through the slot 8, and out again through the slot 9, 40 then around through the slot in which the block s, is inserted, the stuff passing between the block and the side of the slot and through the notch 11, into the hollow shaft, whence it is brought out between the posts H and I, 45 where it is attached to the rope S to be parcelled. Thus as the carriage advances and the wheel W, is revolved in the direction of its arrow the mallet V, is carried around the rope and the parcelling is wound 50 on in a direction counter to that in which the worming was laid, (it may if preferred be wound in the same direction by changing the gears which revolve the mallet V.) When the spool q is emptied it may be removed 55 the same as the spools l. After being parcelled the rope is to be served with spun yarn or other small cord for this purpose, I employ another mallet X (shown detached in Fig. 3) placed between the posts I and K, the hollow shaft of which is supported 60 in suitable boxes in these posts. It carries a gear t which engages with a cog wheel Y, on the shaft M. This mallet carries a spool u, on which the serving yarn v is wound. 65 It is led from the pulley through a hole in

a strip 12 on one side of the mallet, thence through a slot 13, which is cut entirely through the mallet, then over a pulley or sheave w attached to one side of the mallet, then again through the slot 13 into the hollow shaft, whence it is led out beyond the post K and is attached to the rope S. An adjustable guide block y (detached in Fig. 4) is inserted in a slot in the side of the mallet opposite the spool, and is retained in place by a screw 14, (Fig. 3) passing through a small slot. The edge 15 of this block rests in contact with the rope and is grooved out a little to make it lie snug. A tongue 16 projects from one end of this block over the part which is already served and forms a shoulder 17 against which the yarn is pressed and which compels it to wind regularly around the rope without riding or leaving spaces between the turns. 70 75 80 85

The boxes k, in which the hollow shafts of the mallets revolve are made slightly adjustable in height in the posts, that the rope may be kept central in the shafts, notwithstanding that the varying thickness of the rope wound over the windlass P, would vary the position of its center, or the height of the windlass may be made adjustable for this same purpose. 90

The manner described of reeving the yarns 95 and the parcelling through their respective mallets is intended to apply the requisite degree of friction to draw them sufficiently tight around the rope—but it is evident that other means may be employed for this purpose, for instance by applying friction to the spools. 100

The operation of this machine is as follows: The rope S, is lead from the windlass P through the hollow shafts of the mallets and is secured to the gallows Q. It is then drawn taut by the windlass. The mallets being supplied with yarn and parcelling as before described the machine is set in motion, when the carriage D, will be fed along in the direction of its arrow. Then as the mallets are revolved as indicated by their respective arrows the worming will be put on by the mallet R as before described. The carriage then travels along until the part of the rope that has been wormed passes through between the posts H, and I, when the end of the parcelling is attached, and the mallet V continues to wind the parcelling around over the worming. Then as the carriage progresses farther and the portion of the rope which has been parceled comes out beyond the post K, the yarn v is attached and the mallet X serves the yarn over the parcelling, completing the operation. It is obvious that either of these operations may be omitted or either be performed by itself. When the carriage has arrived at the end of the ways B, the pawl h, is lifted and the carriage is run back toward the gallows Q, 110 115 120 125 130

the finished portion of the rope being taken up on the gallows and a fresh portion being paid out over the windlass.

5 The ways may be of any convenient length.

When the machine is first started there will be a short piece of the rope extending from the post F to the gallows which will not be operated upon. If it is required to 10 serve it all the way to its end, another rope may be attached to it to lead it through the hollow shafts of the mallets, when the worming may be commenced close to the end of the rope S.

15 The speed of the several mallets may be varied by changing the gears, or the speed

of the carriage may be changed to suit the different sizes of the rope or of the spun yarn and parceling.

What I claim as my invention and desire 20 to secure by Letters Patent is—

The above described machine, consisting of an arrangement of devices for worming, 25 parceling and serving rope in combination with suitable devices for holding and straining the same, operating in the manner substantially as described.

PATRICK McLAUGHLIN.
